UNITED STATES PATENT OFFICE.

ROBERT LEDING, OF WASHINGTON, DISTRICT OF COLUMBIA.

DESIGN FOR A HANDLE FOR SPOONS, &c.

SPECIFICATION forming part of Design No. 20,649, dated March 31, 1891.

Application filed March 5, 1891. Serial No. 383,915. Term of patent 7 years.

To all whom it may concern:

Be it known that I, ROBERT LEDING, a citizen of the United States, residing at Washington, in the District of Columbia, have invented and produced a new and original Design for Handles for Spoons and Similar Articles, of which the following is a specification, reference being had to the accompanying drawings, forming a part thereof, and wherein—

Figure 1 represents a front or obverse view of a spoon, showing my design applied to its handle; and Fig. 2 represents a rear or reverse view of the same.

The leading features of my design consist of medallion heads of George and Mary Washington, located at the end of the handle, together with the Washington crest beyond said medallion heads.

In the drawings, A is the handle, B is the space occupied by the medallion heads, and C is the Washington crest beyond the medallion heads.

What I claim is—

1. The design for a handle for spoons and similar articles, as shown.
2. The design for the obverse of a handle for spoons and similar articles, as shown.
3. The design for the reverse of a handle for spoons and similar articles, as shown.

In testimony whereof I affix my signature in presence of two witnesses.

ROBERT LEDING.

Witnesses:

JOHN C. PENNIE,
WM. A. EASTERDAY.
